Primary Examiner—Carol Rademaker(74) *Attorney, Agent, or Firm*—Venable LLP; James R. Burdett; Keith G. Haddaway(57) **CLAIM**

The ornamental design for a container dome, as shown and described.

DESCRIPTION

FIG. 1 is a perspective view of a container dome according to the present invention;

FIG. 2 is a front elevational view thereof, the back elevational view being identical;

FIG. 3 is a right side elevational view thereof, the left side elevational view being a mirror identical; and,

FIG. 4 is a top plan view thereof.

The right side view and left side view of the container dome of the second embodiment are identical to the right side view and left side view of the third embodiment.

The right side view and left side view of the container of the fourth and fifth embodiments are identical to the right side view and left side view of the third embodiment.

The top view of the container dome of the second embodiment and top view of the container of the third through fifth embodiments are identical to the top view of the container dome of the first embodiment.
